US0D1099953S

(12) **United States Design Patent** (10) **Patent No.:** **US D1,099,953 S**
(45) **Date of Patent:** **** Oct. 28, 2025**

(54) **DISPLAY SCREEN OR PORTION THEREOF WITH GRAPHICAL USER INTERFACE**

(71) Applicant: **Peloton Interactive, Inc.**, New York, NY (US)

(72) Inventors: **John Paul Foley**, New York, NY (US); **Thomas Philip Cortese**, Summit, NJ (US); **Yu Feng**, New York, NY (US)

(73) Assignee: **Peloton Interactive, Inc.**, New York, NY (US)

(**) Term: **15 Years**

(21) Appl. No.: **29/871,082**

(22) Filed: **Feb. 10, 2023**

Related U.S. Application Data

(63) Continuation of application No. 29/769,303, filed on Feb. 4, 2021, now Pat. No. Des. 978,176, which is a (Continued)
